[57] ABSTRACT

Dilution of aqueous concentrates of alkyl ether sulphates tends to cause the viscosity to rise to levels which are problematical prior to falling to lower levels at concentrations of less than 30%.

The viscosity of the concentrate on dilution can be kept within reasonable bounds by the addition of a compound of the formula

where

R is an alkyl group of from 1 to 4 carbon atoms

Y is a carboxylic group

Ar is a aromatic nucleophile

X is a hydroxyl group or an alkoxy group of 1 to 4 carbon atoms

a is 0 to 3

b is 1 to 3 but is preferably at least 2 if $c + a$ is not 1 or more.

c is 0 to 3 and

μ is 0 to 4

27 Claims, No Drawings

DETERGENT CONCENTRATE

The present invention relates to detergent components, in particular it relates to the sulphates of alkoxylated alcohols more particularly to sulphates of alkoxylated C_8 to C_{24} alcohols such as sulphated ethoxylated lauryl alcohol or mixtures containing lauryl alcohol derivatives, for example those in which the alkyl derivative has a chain with a carbon number ranging from C_8 to C_{18} . Such a feedstock could readily be obtained from coconut or PK oil or commercially available Ziegler or Oxo alcohols.

Aqueous solutions of these compounds are employed in cosmetic, toiletry and detergent compositions for example shampoos and bubble baths and liquid cleaning compositions. Normally these materials are supplied at 28% active ingredient but in the interests of economy in transport and packaging high concentrations of the order of 50 - 70% are also commercially available. At these high concentrations they have the texture of a thick paste. In the final formulation they are normally present in an amount less than 30% active in an aqueous solution.

Unfortunately on dilution of these concentrates with water rather than the viscosity diminishing as might be expected it starts to increase. For example the sodium salt of a sulphate of a di-ethoxylated derivative of the commonly used mixture of alcohols of C_8 to C_{18} with a concentration of 60% active matter the balance being water, has a viscosity of 17,000 centipoises. On dilution to 45% active matter the viscosity increases to greater than 500,000 centipoises. On further dilution the viscosity drops until at the concentration used in shampoos it again becomes liquid.

Although it is possible to employ such concentrates without the incorporation of a viscosity modifier such an increase in the viscosity during dilution naturally contributes substantial problems for the formulator. Such problems include pieces of gel becoming attached to the containers or stirrers employed. Moreover the pieces of gel formed during the dilution are themselves only soluble with difficulty on further dilution.

In order to avoid these problems viscosity modifiers have been incorporated in aqueous concentrates of sulphates of ethoxylated alcohol so as to maintain the viscosity of a solution at high concentrations at a level such that the solutions are reasonably free flowing and are easily diluted to any required concentration. Proposed formulations include that described in British specification No. 1164854 in which the viscosity characteristics of a formulation containing an alkylaryl sulphonate epoxy in alkyl chain of 8 or more carbon atoms and a sulphated alkoxylated alcohol is modified by incorporation of a magnesium salt. British Specification No. 948240 describes the use of substantial quantities of sodium xylene sulphonate or sodium toluene sulphonate as a solubiliser for an alkyl benzene sulphonate / alkyl polyoxyethylene sulphate mixture. In addition to modifying the viscosity of a solution at concentrations in the range of 25 - 75% active matter it is also necessary that any additive employed should not prevent or hinder the effect of thickeners conventionally used such as sodium chloride or ammonium salts, which it may be desired to incorporate in the finished formulation in order to give it an acceptable consistency.

At present this problem is being attacked by the incorporation in the concentrated aqueous sulphate of

ethoxylated alcohol an alcohol of low molecular weight such as isopropanol or ethanol. However the use of such alcohols is disadvantageous in that having high vapour pressures their odour is detectable in the finished formulation and may constitute a fire hazard.

We have found that we can prepare aqueous solutions of salts of sulphated alkoxylated alcohols which have viscosity and dilution properties that enable them to be prepared as concentrates and diluted to normal formulation concentrations without detracting from the properties of such formulations. We can achieve this by incorporating in the aqueous concentrate of the surfactant a sulphonate acid of the formula $R_uY_aAr(SO_3H)_bX_c$ or the alkali metal, or alkaline earth metal, alkanolamine, amine or ammonium salts of such an acid where,

Ar = aromatic nucleus for example benzene or naphthalene, optionally having inert substituents.

R = Lower alkyl groups of from 1 to 4 carbon atoms

Y = carboxylic group

X = hydroxy group or an alkoxy group of from 1 to 4 carbon atoms.

$a = 0$ to 3

$b = 1$ to 3 but is preferably at least 2 unless $c + a$ is one or more

$c = 0$ to 3

$u = 0$ to 4

Examples of such acids are benzene m disulphonic acid, ortho xylene disulphonic acid, meta xylene disulphonic acid, para xylene disulphonic acid, 1,3,5 benzene trisulphonic acid, phenol disulphonic acid, phenol trisulphonic acid, catechol disulphonic acid, and toluene disulphonic acid.

Salts of these acids which may be employed can be those obtained by neutralising all of the acid functions of the acids, including the hydroxyl and carboxylic functions where these are present. Often, however, a lower degree of neutralisation will also provide useful materials.

Accordingly the present invention provides an aqueous concentrate comprising at least 30% by weight of a sulphated alkoxylated alcohol or a water soluble salt thereof and from 1 - 10% by weight based on the weight of solution, of an aromatic sulphonate acid or salt thereof as defined above.

Concentrates which are particularly suitable for modification according to the present invention are those of the sodium salt of the sulphate of an ethoxylated lauryl alcohol having nominally 1 - 4 oxyethylene groups. Other compounds such as the equivalent propoxylated derivatives or the derivatives of other C_8 - C_{13} alcohols may also be employed. Such compounds are frequently in the form of their sodium salts although modifications according to the invention may also be the use of salts such as the potassium, magnesium lithium, ammonium or alkanolamine salts or the acid themselves. Normally the salt of the aromatic sulphonate acid employed will be a salt of the same cation as the cation of the alkoxylated alcohol sulphate salt.

The normally available commercial materials sold as the salts of sulphated alkoxylated alcohols frequently contain electrolytes such as sodium chloride and sodium sulphate and free alkoxylated alcohol. These materials in themselves have an effect on the viscosity of the product, which may in some cases be synergistic with the added viscosity modifiers. However it is not normally desirable to add excessive amounts of inor-

ganic electrolyte (e.g. greater than 10% based on the ether sulphate). Excessive amounts of alkoxylated alcohol tend to separate out of solution and thereby detract from its properties.

Other components which are to be employed in the final formulation may of course also be present in the concentrate. For example there may also be present other surface active agents such as monoalkylolamides, detergent sulphosuccinates, sulphosuccinamates, alkyl sulphate salts or nonionic surface active agents such as polyoxy alkylene ethers and esters.

The concentrate according to the invention normally comprises of at least 50% by weight, often above 70% by weight of sulphonated ethoxylated alcohol and may be diluted by the formulator at any convenient temperature probably in the range 15° to 70°C, to that final concentration required for the formulation. After such dilution other ingredients required for the final product may also be added as desired. From a second aspect therefore the present invention comprises making an aqueous solution of a sulphonated ethoxylated alcohol as previously described of a concentration below 30% by weight by the addition of water to an aqueous concentrate having a content of at least 30% by weight of the sulphonated alkoxylated alcohol and from 1 to 10% by weight based on the weight of solution of an aromatic sulphonic acid as hereinbefore described or a salt thereof.

Compositions according to the invention are illustrated by the following examples.

EXAMPLE 1

Aqueous solutions of commercial sodium lauryl ether (2EtO) sulphate were prepared containing 30, 40 and 50% respectively of the above compound. These materials were non-flowing gels with viscosities in the region between 100,000 and 500,000 cp at 20°C.

Similar solutions were then prepared with the incorporation of disodium benzene disulphonate at various levels. These materials were pourable fluids. The viscosities as measured by a Brookfield viscometer (Spindle LV3 at 3 RPM) are given below.

% ether sulphate	% disodium benzene disulphonate	viscosity cp.
30	2.5	19,000
	5.0	14,200
40	6.0	22,800
	7.5	2,600
50	2.5	20,200
	5.0	9,600

EXAMPLE 2

A solution of commercial sodium lauryl ether (2EtO) sulphate was prepared containing 50% of the above compound plus 2.5% disodium Xylene disulphonate. This material was a pourable fluid at ambient temperatures with a viscosity as measured in Example 1 of 20,500 cp.

EXAMPLE 3

A solution was prepared, as in Example 2 but containing 2.5% of trisodium - 3, 5 - disulphobenzoate. The viscosity of the resultant fluid was 15,000 cp as measured in Example 1.

We claim:

1. An aqueous concentrate comprising 50-70% by weight of a sulphonated alkoxylated alcohol salt, said salt being a water soluble sulphate of an alcohol having 8-24 carbon atoms which has been condensed with a total of from 1 to 4 ethylene oxide or propylene oxide groups, and from 1 to 10% by weight based on the total weight of the concentrate of an aromatic sulphonic acid, said sulphonic acid being an alkali metal, alkaline earth metal, alkanolamine, amine or ammonium salt of an aromatic sulphonic acid of the formula:

where

R is an alkyl group of from 1 to 4 carbon atoms

Y is a carboxylic group

Ar is a benzene nucleus

X is a hydroxyl group or an alkoxy group of from 1 to 4 carbon atoms

a is 0 to 3

b is 2 to 3

c is 0 to 3

u is 0 to 4.

2. An aqueous concentrate as claimed in claim 1 which comprises from 2 to 4% by weight of the said aromatic sulphonic acid.

3. A concentrate as claimed in claim 1 wherein the sulphonated alkoxylated alcohol is a sulphate of an alcohol of from 8 to 18 carbon atoms which has been condensed with a total of from 1 to 4 ethylene oxide or propylene oxide groups.

4. A concentrate as claimed in claim 1 wherein the sulphonated alkoxylated alcohol is in the form of its sodium salt.

5. A concentrate as claimed in claim 4 wherein the sulphonated alkoxylated alcohol is lauryl alcohol condensed with 2 moles of ethylene oxide.

6. A concentrate as claimed in claim 1 wherein the sulphonic acid is benzene meta disulphonic acid.

7. A concentrate as claimed in claim 1 wherein the sulphonic acid is a xylene disulphonic acid.

8. A concentrate as claimed in claim 1 wherein the aromatic sulphonic acid is 1,3,5 benzene trisulphonic acid.

9. A concentrate as claimed in claim 1 wherein the aromatic sulphonic acid is phenol disulphonic acid.

10. A concentrate as claimed in claim 1 wherein the aromatic sulphonic acid is phenol trisulphonic acid.

11. A concentrate as claimed in claim 1 wherein the aromatic sulphonic acid is catechol disulphonic acid.

12. A concentrate as claimed in claim 1 wherein the aromatic sulphonic acid is toluene disulphonic acid.

13. A concentrate as claimed in claim 2, wherein said sulphonated alkoxylated alcohol is lauryl alcohol condensed with two moles of ethylene oxide.

14. A concentrate as claimed in claim 5, wherein said aromatic sulphonic acid is selected from the group consisting of benzene disulphonic acid, xylene disulphonic acid, phenol disulphonic acid, catechol disulphonic acid, toluene disulphonic acid, phenol trisulphonic acid, 1,3,5-benzene trisulphonic acid and 3,5-disulphobenzoic acid.

15. A concentrate as claimed in claim 13, wherein said aromatic sulphonic acid is selected from the group consisting of benzene disulphonic acid, xylene disulphonic acid, phenol disulphonic acid, catechol disulphonic acid, toluene disulphonic acid, phenol trisul-

phonic acid, 1,3,5-benzene trisulphonic acid and 3,5-disulphobenzoic acid.

16. A concentrate as claimed in claim 1, wherein said sulphonate is the sodium salt of the aromatic sulphonic acid.

17. A concentrate as claimed in claim 2, wherein said sulphonate is the sodium salt of the aromatic sulphonic acid.

18. A concentrate as claimed in claim 5, wherein said sulphonate is the sodium salt of the aromatic sulphonic acid.

19. A concentrate as claimed in claim 14, wherein said sulphonate is the sodium salt of the aromatic sulphonic acid.

20. A free-flowing aqueous concentrate comprising an admixture of

i. between 1 and 10% by weight based on the total weight of the concentrate of an aromatic sulphonate, said sulphonate being an alkali metal, alkaline earth metal, alkanolamine, amine or ammonium salt of an aromatic sulphonic acid of the formula:

wherein

R is an alkyl group of from 1 to 4 carbon atoms

Y is a carboxylic group

Ar is a benzene nucleus

X is a hydroxyl group or an alkoxy group of from 1 to 4 carbon atoms

a is 0 to 3

b is 2 to 3

c is 0 to 3

u is 0 to 4; and

ii. an aqueous concentrate comprising between 50 and 70% by weight of a sulphated alkoxylated alcohol salt, said salt being a water soluble sulphate of an alcohol having 8-24 carbon atoms which has

been condensed with a total of from 1 to 4 ethylene oxide or propylene oxide groups, which aqueous concentrate would be a thick paste or gel in the absence of admixture with component (i).

5 21. A concentrate according to claim 20, wherein said component (i) is in an amount of from 2-4% by weight of the said aromatic sulphonate.

22. A concentrate according to claim 20, wherein said sulphated alkoxylated alcohol salt is the sodium salt.

10 23. A concentrate according to claim 22, wherein said sulphated alkoxylated alcohol is lauryl alcohol condensed with two moles of ethylene oxide.

15 24. A concentrate according to claim 23, wherein said aromatic sulphonic acid is selected from the group consisting of benzene disulphonic acid, xylene disulphonic acid, phenol disulphonic acid, catechol disulphonic acid, toluene disulphonic acid, phenol trisulphonic acid, 1,3,5-benzene trisulphonic acid and 3,5-disulphobenzoic acid.

20 25. A concentrate according to claim 24, wherein said aromatic sulphonate is the sodium salt of said aromatic sulphonic acid.

25 26. A concentrate according to claim 21, wherein said aromatic sulphonic acid is selected from the group consisting of benzene disulphonic acid, xylene disulphonic acid, phenol disulphonic acid, catechol disulphonic acid, toluene disulphonic acid, phenol trisulphonic acid, 1,3,5-benzene trisulphonic acid and 3,5-disulphobenzoic acid.

30 27. A concentrate according to claim 26, wherein said sulphated alkoxylated alcohol is lauryl alcohol condensed with two moles of ethylene oxide and wherein said aromatic sulphonate and said sulphated alkoxylated alcohol salt are both in the form of the sodium salt.
